NESTING BASKET CONSTRUCTION

John Clarence Pfeffer, Piedmont, Calif., assignor to Safeway Stores, Incorporated, Oakland, Calif., a corporation of Maryland

Filed May 5, 1958, Ser. No. 733,067

6 Claims. (Cl. 220—19)

This invention relates generally to baskets and trays, and particularly to a nesting basket construction for use in the transporting and storage of crushable items of merchandise.

In the handling of many items of merchandise, particularly foods and other such items, it is frequently desirable to provide a protective basket to prevent crushing or damage to the merchandise. Such basket is used to protect the merchandise during the period of shipment or storage prior to marketing, and then is generally returned to the original shipping point. During the return trip the empty baskets occupy considerable space, and nesting type baskets are sometimes used in an effort to conserve valuable shipping and storage space. However, because of a number of problems presented, these baskets have not proved entirely satisfactory in use. One difficulty is that the baskets are not readily stacked in a secure merchandise carrying position, and tend to slide or topple sideways causing an undesired accidental discharge of the merchandise. Another difficulty is that the baskets do not nest properly, or employ expensive hard-to-use collapsing mechanisms to achieve the nesting functions. A basket construction that would solve these problems would therefore be of great benefit to the art.

In general it is an object of the present invention to improve upon the construction of nesting baskets, particularly with respect to means of preventing shifting of the baskets, either laterally or longitudinally, when the baskets are in a stacked merchandise carrying position.

It is another object of the invention to provide a basket construction of the above type which will permit a ready nesting of baskets having substantially the same rectangular configuration and dimensions.

Another object of the invention is to provide a nesting basket construction that will act positively to protect such merchandise as is contained within its framework, when in a stacked carrying position.

A further object of the invention is to provide a nesting basket construction that is rugged, durable, easily manufactured and which employs no moving parts. Additional objects and advantages of the invention will appear from the following description and from the drawings in which:

Figure 1 is a view in perspective of a basket construction embodying the invention;

Figure 2 is a view in elevation showing several baskets arranged in a stacked carrying position;

Figure 3 is a like view, illustrating the manner of nesting the baskets when not in use.

In terms of broad inclusion, a nesting basket of the present invention comprises a pair of unitary substantially rectangular upper and lower frames each having long and short sides, and side frame means joining such frames to provide the basket construction. Each of the long sides of the upper frame has a pair of upper projections spaced from one another a distance greater than the length of the short side, whereas each of the long sides of the lower frame is provided with a pair of

2

recesses having inner portions spaced from one another a distance slightly less than the length of a short side. In other respects the upper and lower frames are substantially identical in construction and size, the lower frame being slightly smaller in size as appearing herein-after. The side frame means preferably include a plurality of linear segments arranged symmetrically along a side in a downwardly tapering configuration. This construction allows the side frame segments of one basket to nestingly receive the side frame segments of adjacent baskets in a nested parallel relation of the baskets. In a cross stacked or carrying position of the baskets, the projections of the upper frame prevent longitudinal sliding of an upper adjacent basket; in like fashion the recesses of the lower frame prevent lateral sliding of a lower adjacent basket. As a result the effects of swaying or lurching movements in transport, tending to topple a stack of baskets or otherwise cause damage to the supported merchandise, are reduced to a minimum.

Referring to the drawings in detail, 10 represents a nesting basket construction which may be stacked in a carrying position, as illustrated in Figure 2, or in a nested position, as illustrated in Figure 3. Each of the basket constructions comprises an upper frame 12 and a lower frame 14. The upper frame is substantially rectangular and is preferably bent from a single piece of wire or tubing to provide long sides 16 and short sides 18 as illustrated. Each of the long sides 16 is provided with a pair of upward projections 20, preferably bent from the material of the frame. These projections are spaced from one another along the side a distance determined to be greater than the length of a short side of the basket. The lower frame 14 can be similarly fabricated to provide long sides 22 and short sides 24. Each long side 22 is provided adjacent its end with a recess 26, which also is preferably bent from the material of the frame. The recesses 26 of a side are spaced from one another in such fashion that the inner portions 27 are at a distance slightly less than the length of a short side of the basket. As previously indicated, the sides 16 and 18 of the upper frame 12 are slightly longer than the corresponding sides 22 and 24 of the lower frame 14.

The upper and lower frames are substantially parallel to one another and are joined by a plurality of linear segments 30 which constitute the side frames of the basket. Preferably the segments of each side of the basket are arranged in planes substantially perpendicular to the planes of the upper and lower frames, with the segments of each side being symmetrically arranged in a downwardly tapering configuration, as is best illustrated in Figure 2. In this arrangement, the outer dimension or length of the lower frame 14, measured between the outer surfaces of the sides 24, plus the thickness or diameter of linear segments 30 on each end, is substantially the same as the internal dimension or length of the upper frame 12, measured between the inner surfaces of the sides 18, and similarly, the outer dimension or width of the lower frame 14, measured between the outer surfaces of the sides 22, plus the thickness or diameter of the linear segments 30 on each side, is substantially the same as the internal dimension or width of the upper frame 12, measured between the inner surfaces of the sides 16. This construction permits a nesting of a plurality of trays, when arranged in a parallel stacked relation, as illustrated in Figure 3. The linear segments 30 of adjacent baskets lie in the same plane. As an upper basket is being lowered into nesting relation with a lower basket, the lower end of each rod of the segments 30 in the upper basket is disposed between the upper ends of the rods of the segments 30 in the lower basket and lie in the same plane. The upper basket is lowered into the lower basket until the sides of the segments 30

in the upper basket engage the sides of the corresponding segments in the lower basket, as shown in Fig. 2, which limits the nesting relation. This engagement of segments of the upper and lower baskets takes place on all four sides. As will be observed each symmetrical pair of segments 30 on a side are received by a cooperating pair of symmetrical segments in the basket next above or below. Preferably the upper ends 29 of the segments are secured inwardly adjacent the upper frame 12 and the lower ends 31 of the segments are secured outwardly adjacent the lower frame 14 to facilitate this nesting function. This construction is best illustrated in Figure 1.

In the arrangement described above, the planes of the segments 30 are disposed perpendicularly of the planes of the upper and lower frames, and the segments 30 on one side are disposed parallel with the segments on the opposite side of a basket. It is evident, however, that the lower frame 14 could be made smaller than shown in the drawings and described above, which would result in a tapering of the planes of the segments 30. This arrangement, however, would not interfere with the nesting operation, wherein superimposed baskets would come to rest, in nested relation, with the sides of the rods of the segments 30 of the upper basket engaging the sides of the rods of the corresponding segments 30 of the lower basket.

To complete the basket construction a plurality of cross bracing members 32 and 34 can be provided in any suitable relationship to provide a bottom or supporting base to the basket construction. Preferably this bottom is slightly raised above the lower frame 14 so that cross stacking of the baskets can be readily accomplished in the manner hereinafter to be described. One or more side reinforcing members 36 can also be provided, as may be necessary. Where provided, the reinforcing members 36 can be so disposed as to engage the upper edges of an upward projection 20 of an adjacent basket at the same time that the segments are brought into engagement, as shown in Fig. 3, to prevent wedging or jamming between adjoining baskets.

In the use of the device as just described, the baskets 10 can be filled with merchandise and stacked for shipment or storage as illustrated in Figure 3. In the stacked position, the merchandise within the baskets is protected from impact or other damage during all normal handling of the rigid framework of the carrying basket. By way of illustration, a palleted stack of loaded baskets can be easily lifted and moved about by means of a fork-lift truck or in fact, by any suitable handling device. During such handling, no shifting of the baskets can occur in any direction, the shifting being prevented by the co-operation of the pairs of projections 20 in the long sides of the upper frame and the pairs of recesses 26 provided in the long sides of the lower frame. It will be understood that in the cross stacked position illustrated, the projections and recesses of the opposed contacting frames 12 and 14 of the baskets firmly engage one another to prevent shifting either laterally or longitudinally. When the merchandise reaches its ultimate destination, and is unloaded from the baskets, the baskets may be advantageously nested in the position illustrated in Figure 3. The nesting operation is facilitated by the substantially self-nesting characteristic of the pairs of linear segments 30 which make up the sides of the baskets. Since a stack of nested trays, as in Figure 3, will occupy less than half the space of the stacked trays, as in Figure 2, a maximum use of available space is made possible. This is a factor of considerable economic importance since the shipping or storage space saved by the nesting can be employed for other purposes.

The many advantages of the present invention can be summarized as follows: The baskets have large carrying capacity yet are easily nested in a parallel stacked relation. The baskets have a self-nesting characteristic and in a nested position occupy less than half their total

volume. During a normal carrying use, and in a cross stacked carrying position, the possibility of shifting of the baskets in such manner as to cause toppling of the stack is virtually eliminated. Relatively heavy gauge wire or rodding can be employed in making the baskets, without reliance on comparatively weak mesh work or on expensive machined frame members for the nesting function. The baskets can also advantageously be fabricated in a substantially square or rectangular form that facilitates the storage of merchandise in the basket, and which eliminates the problems normally encountered with conventional tapered types of nesting baskets.

I claim:

1. In a nesting basket construction, a unitary substantially rectangular upper frame and a unitary substantially rectangular lower frame, said frames being substantially identical in size and parallel to one another, and side frames connecting said upper and lower frames, said side frames being perpendicular to the planes of said upper and lower parallel frames to thereby provide a basket of substantially rectangular configuration, each of said side frames consisting of linear segments arranged symmetrically on the sides of the basket so as to taper towards the centers of the sides from top to bottom, whereby each perpendicular side frame is adapted to be nestingly received within a corresponding side frame of another similar basket construction, when the basket constructions are arranged in parallel nesting relation, and whereby the linear segments of one basket engage the corresponding linear segments of an adjacent basket to limit the nesting relationship.

2. In a nesting basket construction, a unitary substantially rectangular upper frame, a unitary substantially rectangular lower frame, said frames being parallel to one another and each having long and short sides, the dimensions of the lower frame being slightly less than the corresponding dimensions of the upper frame, and perpendicular side frame means joining said upper and lower frames into a basket construction of substantially rectangular configuration, said side frame means consisting of linear segments secured inwardly adjacent the upper frame and outwardly adjacent to the lower frame, the linear segments of each side frame means being symmetrically arranged to taper inwardly from top to bottom, whereby a perpendicular side frame means can be nestingly received within a corresponding, perpendicular side frame means of another similar basket construction, and whereby the linear segments of one basket engage the corresponding linear segments of an adjacent basket to limit the nesting relationship.

3. The basket construction of claim 2 wherein each long side of the upper frame is provided with a pair of upward projections spaced from one another a distance greater than the length of the short side, whereby in a cross stacked relation of the baskets, the upper basket will be prevented from shifting longitudinally of the lower basket.

4. The device of claim 3, including a reinforcing member disposed intermediate the upper and lower frames and surrounding said linear segments, said reinforcing member being disposed in a position to engage the upward projections of a lower basket, when in nested relation, simultaneously with the engagement of the linear segments, to prevent jamming between nested baskets.

5. The device of claim 4 wherein each long side of a lower frame is provided with a pair of recesses having inner portions spaced from one another a distance slightly less than the length of a short side, whereby when said baskets are arranged in cross stacked relation, an upper basket will be prevented from shifting laterally of a lower basket.

6. In a nesting basket construction, a unitary substantially rectangular upper frame having long and short sides, each long side having a pair of upper projec-

tions spaced from one another a distance greater than the length of the short side, a unitary substantially rectangular lower frame also having long and short sides, each long side of said lower frame having a pair of recesses having inner portions spaced from one another a distance slightly less than the length of a short side, said upper and lower frames being parallel to one another and, the dimensions of the lower frame being slightly less than the corresponding dimensions of the upper frame, and substantially perpendicular side frame means joining said lower and upper frames to form a substantially rectangular basket nestable with other similar baskets in a stacked parallel relation, said perpendicular side frame means each including a plurality of linear segments symmetrically arranged along the side so as to taper toward the center of the side frame from top to bottom, said linear segments each being secured at its upper end to the outer edge of said upper frame and at its lower end to the outer edge of said lower frame, whereby the linear segments of one basket engage the corresponding linear segments of an adjacent basket to

limit the nesting relationship, and whereby the projections on said upper frame and the recesses on said lower frame allowing said baskets to be cross stacked with other baskets in such manner as to resist shifting in 5 either a lateral or a longitudinal direction.
